UNITED STATES PATENT OFFICE.

PEARL N. JONES, OF PITTSBURGH, PENNSYLVANIA.

PASSENGER-CAR.

1,130,296.

Specification of Letters Patent. Patented Mar. 2, 1915.

Application filed September 23, 1912. Serial No. 721,789.

To all whom it may concern:

Be it known that I, PEARL N. JONES, a resident of Pittsburgh, county of Allegheny, and State of Pennsylvania, have 5 invented new and useful Improvements in Passenger-Cars, of which the following is a full, clear, and exact description, reference being had to the accompanying drawings, forming part of this specification, in 10 which—

Figure 1 is a sectional plan view of one type of car embodying my invention; Fig. 2 is a side elevation showing the entrance and exit doors in their open position; Fig. 15 3 is a longitudinal section on the line III—III of Fig. 1; Fig. 4 is a transverse section on the line IV—IV of Fig. 1; Fig. 5 is a perspective view of a portion of the car floor and steps; and Fig. 6 is a similar 20 view showing a modification.

My invention has relation to passenger cars, and more particularly to what are commonly known as "street" cars.

One object of my invention is to provide 25 a car having a novel arrangement of its exit and entrance passages, whereby the incoming and outgoing passengers will not only be separated and prevented from interfering with each other within the car, but 30 which will also separate the entering and alighting passengers exteriorly of the car on the street.

In central-entrance cars as heretofore used, the entrance and exit passages have 35 been closely adjacent to each other, and there has been interference between the incoming and outgoing passengers within the car due to the crowding of incoming passengers adjacent to the exit opening and of 40 outgoing passengers adjacent to the entrance opening. My invention is designed to overcome this by a novel arrangement of central-entrance passages and front side-exits. My invention also provides a car in 45 which the responsibility of looking after the car is divided between the motorman and the conductor. The increasing size of the street car has increased the work of the crew, and in cars having a single door or 50 adjacent doors for entrance and exit, that member of the crew (motorman or conductor) who looks after the operation of the doors in addition to performing his ordinary duties, has more than half the work 55 to perform, resulting in loss of time and delay to schedule. In cars of the central exit and entrance type, the conductor

usually has too much to look after, since he is required to look after both the entering and alighting passengers, to control both 60 the entrance and exit doors, and also to collect fares from the entering passengers. In cars constructed in accordance with my invention, this work may be divided, and while the conductor retains control of the 65 entrance doors, entering passengers, collecting fares, etc., the motorman is given control of the exit door.

Another object of my invention is to reduce the height of the steps leading into 70 the car by means of a ramp or ramps leading from the step toward the level of the floor of the car.

The precise nature of my invention will be best understood by reference to the accompanying drawings, which will now be described; it being premised, however, that various changes may be made in the details of construction and arrangement of the parts without departing from the spirit 80 and scope of my invention as defined in the appended claims.

Referring to the accompanying drawings in which I have shown my invention applied to one form of car, the numeral 2 85 designates the sides of the car which are provided with the usual windows 3. The sides of the car at the central portion thereof extend considerably below the ends or main body-portion of the car, as indicated 90 at 4.

5 is a lower step within the car body at the central portion thereof and adjacent to the central opening 6, which is closed by means of the doors 7, operated by any well-known mechanism.

It can be seen by reference to the accompanying drawings that I have provided a central entrance from both sides of the central portion of the car, and have also provided an exit at each end, but will only describe one of such entrances and exits; it being understood that when the car is moving in one direction the front exit is open, while the opening leading from the rear 105 to the left hand side of the car is closed, and the side entrance leading from the left hand side is also closed, while the side entrance leading from the right hand side is open to permit the passengers to enter the 110 car.

8 designates a step above the step 5, and 9 is a platform which is located on the longitudinal center of the car and approximately

in the central portion of the car body. Extending from the step 8 to the platform 9 is a ramp 10, and extending from the platform 9 in each direction to the level of the floor 5 of the car are ramps 11.

12 designates the fare box which is located at the edge of the platform 9 at the side adjacent to the closed door, and 13 are rails along the edges of the ramp 10 adjacent to 10 the entrance opening 6. The rails 13 and the fare box 12 are removable so that their position can be reversed when the car is run in the opposite direction from that indicated in the drawings.

15 At the front of the car and at the right hand side of the motorman is an exit which is closed by means of doors 14.

15 and 16 are steps leading from the floor level outwardly to the doorway, both of these 20 steps being within the body of the car.

The door 14 at the front of the car is shown open in the drawings to indicate that this door is being used for the exit. The rear door is always closed when the car is run in the direction indicated by the arrow 25 in Fig. 1.

In Fig. 6 I have shown a modification in which the transversely extending ramps are omitted. In this form, the steps are directly 30 to a platform 17. From this platform 17 longitudinally extending ramps 18 of the full width of the car floor lead up to the floor level proper at the respective ends.

It will readily be understood by those 35 familiar with the art that the angle of the ramps and their location can readily be changed to meet the requirements of various car structures.

By the arrangement which is described, I 40 am enabled to materially reduce the height of the steps, and particularly when used with the construction of low-truck cars.

The advantages of my invention result 45 from the provision of a car having a side entrance at the central portion thereof and a front end side exit, so that the entrance is under the control of the conductor, and the exit under the control of the motorman. Further, from the provision of a car in 50 which the exit and entrance are remote from each other, thereby avoiding confusion within the car, as well as on the street. Further, from the provision of one or more ramps leading from the steps to the level of the 55 car floor, whereby the height of the steps is materially decreased, without increasing the number of steps.

The car herein described may also be used 60 to advantage by causing the passengers to enter at the front doorway and leave at the center doorway, in which case they may be required to pay their fare in passing out by the fare box 12. This makes the car a "pay-as-you-leave" car. Or, all passengers may 65 be required to enter at the front door, those

passing to the rear portion of the car paying as they pass the fare box 12, while those entering the front portion of the car would pay as they pass this fare box in leaving the car. This makes the car half "pay-as-you-enter" and half "pay-as-you-leave".

I claim:

1. A passenger car without interior partitions, having a side doorway at the central portion of the car, a step within the car adjacent to said doorway, and a ramp extending transversely from the step toward the longitudinal center of the car; substantially as described.

2. A passenger car without interior partitions, having a side doorway at the central portion of the car, and a ramp extending transversely of the car from the doorway toward the longitudinal center of the car; substantially as described.

3. A passenger car without interior partitions, having side doorways at the central portion of the car, steps within the car adjacent to each of said side doorways, and transversely extending ramps leading from the steps toward the longitudinal center of the car; substantially as described.

4. A passenger car without interior partitions, having side doorways at the central portion of the car, steps within the car adjacent to each of said side doorways, transversely extending ramps leading from the steps toward the longitudinal center of the car, and a front doorway adjacent to the motorman; substantially as described.

5. A passenger car without interior partitions, having side doorways at the central portion of the car, a platform below the level of the floor and approximately on the longitudinal and transverse centers of the car, steps within the car adjacent to each of the side doorways, ramps extending transversely from the steps toward the platform, longitudinally extending ramps leading from the platform to the level of the floor of the car, and a front doorway adjacent to the motorman; substantially as described.

6. A passenger car, having a side doorway at the central portion of the car, a step within the car adjacent to said doorway, and a ramp extending transversely from the step toward the longitudinal center of the car; substantially as described.

7. A passenger car having a side doorway at the central portion of the car, a step within the car adjacent to said doorway, a central level platform portion, a ramp extending transversely from the step toward the central platform, and a fare box adjacent to said platform, said platform forming a conductor stand adjacent to the fare box; substantially as described.

8. A passenger car provided with wheels or trucks adjacent opposite ends of said car, level floors above said wheels or trucks, and

5 a platform disposed below the level of and substantially central with respect to said floors, said platform comprising a substantially level central portion, and inclines extending laterally from said central portion.

9. A passenger car provided with wheels or trucks adjacent opposite ends of said car, level floors above said wheels or trucks, a platform disposed below the level of and substantially central with respect to said floors, said platform comprising a substantially level central portion, and inclines extending from said level floors above the wheels or trucks toward said platform.

10. In a railway car, a floor provided with a depressed platform for entrance and exit, midway of the length of the car, with raised end portions, and with longitudinally sloping floor portions connecting said middle and end portions, said depressed platform sloping downwardly from the middle toward each side.

11. A passenger car provided with wheels or trucks adjacent opposite ends of said car, level floors above said wheels or trucks, a platform disposed below the level of and substantially central with respect to said floors, said platform comprising a substantially level central portion, and inclines extending laterally from said central portion, and inclines extending from said level floors above the wheels or trucks toward and to the level of said platform.

12. A passenger car having a side doorway at the central portion of the car, a step within the car adjacent to said doorway, and a ramp extending transversely from the step toward the longitudinal center of the car; substantially as described.

13. A passenger car having door openings at opposite sides of its central portion, a level platform located within the car between said openings, and ramps extending transversely from the openings toward said platform; substantially as described.

14. A passenger car having oppositely located door openings at its central portion, a step adjacent to each door opening and within the side lines of the car, and transversely extending ramps leading from said steps toward the longitudinal center of the car; substantially as described.

15. A passenger car having wheels or trucks adjacent opposite ends thereof, level floors above said wheels or trucks, and longitudinally extending ramps leading from the central portion of the car upwardly to said level floors, said ramps being of less transverse width than the width of the car body, and said level floors extending at each side of the ramps; substantially as described.

16. A passenger car provided with wheels or trucks near its ends, and having level

65 floors over the wheels or trucks, said car having a central side door opening leading into the body of the car, and a longitudinally extending ramp extending from the center of the car upwardly to the level floor, said ramp being of less transverse width than the width of the interior of the car, and 70 the level floor having portions extending at the sides of the ramp; substantially as described.

17. A passenger car having a side doorway at the central portion of the car, a 75 centrally arranged platform to which said doorway leads, and a ramp extending upwardly from said platform toward the end of the car, said ramp being of less transverse width than the width of the car body, 80 and there being level floor spaces at each side of the ramp; substantially as described.

18. A passenger car having a level floor over its trucks, a relatively depressed central portion between the trucks, and a ramp leading longitudinally from said depressed portion to the level of the floor, the ramp being of less transverse width than the car body and there being a level floor space at the side of the ramp; substantially as described. 90

19. A passenger car having oppositely arranged door openings at its central portion, steps at said door openings within the car body, a platform between the steps, transverse ramps leading from the steps to the 95 platform, and longitudinal ramps leading from the platform toward the ends of the car; substantially as described.

20. A passenger car having oppositely arranged door openings at its central portion, 100 steps at said door openings within the car body, a platform between the steps, transverse ramps leading from the steps to the platform, and longitudinal ramps leading from the platform toward the ends of the 105 car, said ramps being narrower than the width of the car and there being a level floor space at the side of the ramps; substantially as described.

21. A passenger car having a side door 110 opening at its central portion, a step within the car body adjacent to said door opening, a ramp extending transversely of the car from the step toward the longitudinal center of the car, and another ramp extending 115 longitudinally toward the end portion of the car, said ramp being of less width than the width of the car and there being a level floor space at the side of the ramp; substantially as described. 120

In testimony whereof, I have hereunto set my hand.
